United States Patent Office

Des. 221,490
Patented Aug. 17, 1971

221,490

DESK CALENDAR HOLDER

Henry Finkel, Westmount, Quebec, Canada, assignor to
W. L. Plastics and Metal Producers Co., Ltd.

Filed Feb. 26, 1970, Ser. No. 21,644

Term of patent 14 years

Int. Cl. D19—03

U.S. Cl. D74—5

FIG 3

FIG 2

FIG 1

FIG. 1 is a front perspective view of a desk calendar holder showing my new design;

FIG. 2 is a rear perspective view thereof; and
FIG. 3 is a side elevational view thereof.

I claim:

The ornamental design for a desk calendar holder, as shown.
